UNITED STATES PATENT OFFICE.

CHARLES E. GOOGINS, OF BROOKLYN, NEW YORK.

STEAM-BOILER FURNACE.

1,140,674.

Specification of Letters Patent. Patented May 25, 1915.

Application filed June 15, 1914. Serial No. 845,134.

To all whom it may concern:

Be it known that I, CHARLES E. GOOGINS, a citizen of the United States, residing at Brooklyn, in the county of Kings and State 5 of New York, have invented certain new and useful Improvements in Steam-Boiler Furnaces, of which the following is a specification.

This invention relates to steam boiler furnaces, and belongs in the same class of fuel burning and feeding apparatus with the contrivances described and claimed in Letters Patent of the United States No. 795,388, dated July 25, 1905, issued to me, and upon 15 which this invention is believed to be an improvement, with respect to the initial serving and coking of the fuel and devices for performing those operations, and as regards the means for supporting and moving 20 the grate bars.

The special construction and arrangement of the parts comprised in this invention are illustrated in the accompanying drawings, of which—

25 Figure 1 represents a vertical, longitudinal section of all parts assembled. Fig. 2 is a front view of the front wall of the furnace described as a movable wall, and shows the operating members borne by the wall. 30 The section in Fig. 1, is on broken line $x-x$ in Fig. 2.

In the drawings and throughout the description, the same letter or numeral is employed to refer to the same part.

35 Considering the drawings, the floor of the furnace, designated by the letter A, has erected thereon the side walls a and a' . Upon the floor are the track rails B and b, and upon the track is the carriage C movable out and in with respect to the furnace walls upon the wheels c that engage the rails of the track as illustrated. The carriage supports a front furnace wall D, and that portion of the frame of the carriage 45 attached to and extending outside the wall D is provided with a transverse driving shaft d, held in suitable bearings E and revolved by the pulley e, or in some other convenient and usual way. The shaft d operates two eccentrics F and G having the arms f and g. The arms are each provided with a movable sleeve such as the sleeve H on the arm f, and the sleeve is adjustable lengthwise upon the arm by means of the 50 threaded end h of the arm engaging the handwheel J having a threaded hub. Upper

and lower nuts j and j' lock the hand wheel and sleeve in an adjusted position.

Pivots secured to the sleeve H is the forked end of a crank arm K, and the arm is attached to and operates a transverse shaft k journaled in that portion of the frame of the carriage C fixed upon the front or outside of the wall D. Upon the shaft k there is a partly toothed gear wheel 65 L, and this gear meshes with a like gear M on another transverse shaft N similar to the shaft k. The transverse shafts k and N are rocked by the gears and arms O and P fixed to those shafts are correspondingly moved. 70 By means of the adjustable connecting rods Q and R, to the two portions r and S of the inclined grate are reciprocated in a slanting direction. The grates are movably supported upon the wheels or rollers T and t 75 that are revoluble in suitable bearings on the carriage frame below the grate. It will be understood that, as illustrated in Fig. 2, there are four rollers for one portion of the movable grate, and four rollers for the other 80 portion. The grooved guides U and u secured to the under sides of the portions r and S, guide those portions on the rollers. The grate bars V and v are of the flat, perforated type and overlap each other. They 85 move slantingly up and down with respect to each other.

At the lower end of the inclined grates is located a rotary dumping grate W, on the shaft w, and having the air openings y between the bars. Grate W revolves rearwardly, sweeping an apron 1, by which all the burned fuel is directed upon the grate W. The sprocket wheel 2 on the shaft w, connected by chain 3, sprockets 4, and chain 95 5, with the sprocket 6 on the shaft d, turns the grate W. It will occasionally happen that clinkers or large, hard masses of ash carried around by grate W, will strike the pivoted bar 7. In that case, the arm 8, 100 which is rigidly attached to the bar 7, operates the connecting rod 9, and bell crank 10, raising the weight 12, and allowing the clinkers to pass downwardly into the ash space. The weight 11 returns the bar 7 to 105 its original position. The weight is adjustable upon the threaded end 12 of the bell crank 10.

Supported by the furnace arch above the front wall D, is a hopper 13, into which the 110 fuel is fed from any source. The hopper opens downwardly upon a movable pusher

plate 14, arranged to slide upon an external fuel-receiving plate 15, usually inclined as illustrated, and borne by or forming a part of the front wall D. The pusher plate is operated by means of the adjustable connecting rod 16 pivotally connected with the rocking arm 17 that is attached to the transverse rocking shaft 18 journaled in that part of the frame of the carriage which is attached to the outside of the wall D. Rocking arm 19 is actuated by the shaft 18, and the arm is pivotally attached to a connecting rod 20, which assists in operating the pusher-plate. A rocking arm 21 on the shaft 18 has a forked end similar to that of the arm K, and the forked end pivotally connects with a sleeve adjustable upon the eccentric arm g in the manner described for the sleeve H.

20 The function of the pusher plate is to move the fuel from the hopper along the inclined external plate 15 through the throat 22 and upon the coking grate 23 that is arranged next to the wall D on the inside and is supported by the wall. The coking grate is substantially a perforated continuation of the plate 15, and it will be observed in Fig. 1 that the higher end of the inclined or burning grate meets the lower end of the coking grate. Beneath the coking grate is a blast chamber 24 into which air is forced by the blower 25 supported upon the outside of the wall D, and the air is thus directly delivered under pressure to 35 the fuel upon the coking grate. The blower is operated by pulley 26, belt 27, and pulley 28 on the driving shaft d.

In the operation of this invention, fuel from the hopper is pushed along inclined 40 plate 15 upon the coking grate, also inclined as shown. Air from the blast chamber 24 is sent through it directly and it is, to a greater or less degree coked, its volatile, smoke-producing constituents being expelled, to be subsequently sucked down over the blazing fuel on the burning grate and there fully consumed. The pusher plate moves the fuel both on plate 15 and the coking grate by reason of its continuity, and 50 the coked fuel is delivered upon the upper end of the burning grate. The reciprocating grate bars shake it down as fast as may be desired, and the ashes are dumped by the rotary dumping grate.

55 It is thought to be discernable from Fig. 1 that by increasing or decreasing the lengths of the eccentric arms f and g, the positions and movement of the grate bars, and the position and movement of the pusher plate may be altered. For example, the longer the arm f is made the less will be the angle between the arm f and the crank arm K, fewer the teeth of the partial gears which will mesh, and the less will be 65 the relative movements of the grate bars

with respect to each other. Similarly, the longer the eccentric arm g, the farther the end of the pusher plate will be from the coking grate at the lower end of its inclined excursion. The adjustment of the partly toothed gears controls the movements of the grate bars, for the reason that one gear actuates the operating means for one of the two sets of grate bars, and the other gear does the same with relation to the other set of grate bars. In regard to the adjustment of the pusher-plate on the fuel-receiving plate, it is necessary in practice to push certain kinds of coal almost through the throat 22, while other kinds need only be moved along the inclined plate 15. If proper adjustments are made, a particular kind or quality of fuel may be first delivered to the coking grate at any quantity rate, and, subsequently and independently moved along by the movable bars of the burning grate.

It is believed that this invention may be advantageously used with fuel from widely different mines, and that excessive smoking will practically always be prevented with ordinary care.

Having now described this invention and explained the mode of its operation, what I claim is:

1. In a furnace, the combination with the front wall, of parallel transverse shafts rotatively supported on the outside of the front wall, arms attached to the said shafts, a grate having portions each movable back and forth, rods connecting the said arms and the movable portions of the grate, gears connecting the said shafts, a second arm attached to one of the said shafts, a transverse driving shaft arranged upon the front wall below said parallel shafts, an upwardly extending arm having its upper portion pivotally connected with the said second arm, and means connected with the driving shaft and constructed to move the said upwardly extending arm up and down in the direction of its length.

2. In a furnace, the combination with the front wall, of parallel transverse shafts rotatively supported on the outside of the front wall, arms attached to the said shafts, a grate having portions each movable back and forth, rods connecting the said arms and the movable portions of the grate, gears connecting the said shafts, a second arm attached to one of the said shafts, a transverse driving shaft arranged upon the front wall below said parallel shafts, an upwardly extending arm having its upper portion pivotally connected with the said second arm, means constructed to move the said upwardly extending arm up and down in the direction of its length and actuated by the driving shaft, and means carried by the said arm for changing its length between the

driving shaft and the pivotal connection with said second arm.

3. In a furnace, the combination with the front wall, of parallel transverse shafts relatively supported on the outside of the front wall, arms attached to the said shafts, a grate having portions each movable back and forth, rods connecting the said arms and the movable portions of the grate, gears connecting the said shafts, a second arm attached to one of the said shafts, a transverse driving shaft arranged upon the front wall below said parallel shafts, an upwardly extending arm, and an eccentric upon the

driving shaft connected with the said upwardly extending arm for moving the said arm up and down in the direction of its length, the upper portion of the said upwardly extending arm being adjustable in the direction of the length of the arm and having a pivotal connection with the said second arm. 15

In testimony whereof I affix my signature in presence of two witnesses.

CHARLES E. GOOGINS.
